LOUIS VINCENT BARRETT, SR., OF SUMMITHILL, PENNSYLVANIA, ASSIGNOR OF ONE-TENTH TO ANDREW BRESLIN, OF SUMMITHILL, PENNSYLVANIA.

GARMENT-FASTENER.

1,197,431.

Specification of Letters Patent. Patented Sept. 5, 1916.

Application filed February 18, 1913. Serial No. 749,203.

To all whom it may concern:

Be it known that I, LOUIS V. BARRETT, Sr., a citizen of the United States, residing at Summithill, in the county of Carbon and 5 State of Pennsylvania, have invented a new and useful Garment-Fastener, of which the following is a specification.

This invention has reference to improvements in garment fasteners of the type commonly known as hooks and eyes, and its object is to provide a simple device in which both members corresponding to the hook and eye of the named type of garment fastener are identical and both are in reality in the 15 form of eyes so that both members of the fastener may be made by one machine, and furthermore both members of the fastener may be made of wire of the gage usually employed in hooks and eyes and still the device be amply strong for the purposes for 20 which it is intended.

Each eye is made of a single piece of wire bent intermediately upon itself with the free ends curled into small rings, while at the 25 intermediate end the eye is somewhat elongated or elliptical and the elongated eye is dished, so that one eye may be introduced into the other with the dished or concaved portions in opposition and interlocked.

The invention will be best understood from a consideration of the following detailed description, taken in connection with the accompanying drawings forming a part of this specification, with the further understanding that while the drawings show a 35 practical embodiment of the invention, the latter is not confined to any strict conformity with the showing of the drawings, but may be changed and modified so long as 40 such changes and modifications mark no material departure from the salient features of the invention.

In the drawings:—Figure 1 is a plan view of two separated fastening members which 45 together constitute a garment fastener. Fig. 2 is an edge view of the two members shown in Fig. 1. Fig. 3 is a plan view of the garment fastener with the two members in interlocked relation. Fig. 4 is an edge view 50 of the arrangement shown in Fig. 3. Fig. 5 is a perspective view showing one manner of introducing one of the two members of the garment fastener into the other for movement into the interlocked position. 55 Fig. 6 is a plan view illustrating a use of a

single one of the members in conjunction with a button. Fig. 7 is an edge view of the arrangement shown in Fig. 6 but in the interlocked or buttoned position.

Referring to the drawings there are shown 60 two identical members A, B, either of which may be introduced into the other and interlocked therewith in a manner to be described. Since the two members are identical a description of one will apply with equal force 65 to the other, and hence the same reference numerals are employed on both. Each member comprises an eye or loop 1 made by bending a piece of wire of suitable length and gage intermediately upon itself. The front 70 or nose 2 of the loop 1 is rounded and the loop is then gradually expanded at the sides 3 to a point 4 which may be somewhat more than half the length of the longer axis of the loop from the nose 2. From the point 75 4 the sides 5 of the loop approach and are nearly straight until these sides 5 meet in a shank portion 6 of the member where the two legs of the piece of wire bent intermediately upon itself are in contact or approximately so, and finally the free ends of the 80 legs of the bent wire are curved in opposite directions to form oppositely disposed closed rings 7, although it is not essential that these rings be actually fully closed. The 85 loop 1 is also curved in the direction of the long or longitudinal axis of the loop, so that the loop is slightly dished, wherefore the side portions 5 extend slightly to one side of the plane of the shank 6, while the side 90 portions 3 and the nose 2 extend to the other side of said plane.

Suppose, now, that the two members A and B with the longitudinally curved loops 1 are attached by the rings 7 and suitable 95 stitching to two members of a garment to be secured together with, however, the nose portions of the loops 1 of the members A and B in reverse relation, that is, the loops 1, say, of the members A along one edge of 100 the garment having the nose portions directed outwardly from the outer surface of the garment, while the members B have the nose portions of the loops 1 directed inwardly toward the inner surface of the 105 garment, this disposition of the parts being indicated in Fig. 2. If it be desired to secure the two members of the garment together by means of the members A and B one of the members, say, the member B, is 110

turned so that the shorter axis of the loop 1, which is an elongated loop of generally elliptical outline, corresponds in direction to the longitudinal or longer axis of the loop 1 of the member B. The nose portion 2 of the member B is then moved into and through the loop 1 of the member A from the convex side of the loop until the loop of member B has been passed through the loop 10 of the member A, whereupon the member B is turned on its longitudinal axis and also turned on a transverse axis until the convex sides of the loops of the two members face each other and then the two members are 15 drawn apart until the side portions 5 of the member B lodge against the side portions 3 of the member A with the nose portion 2 of the member A in overriding relation to the shank 6 of the member B where the loop 1 of the member A and the shank 6 thereof join. 20 The nose portion of the member B is brought into overriding relation to and engagement with the shank portion 6 of the member B where the loop 1 of the member A and the shank 6 thereof join. 25 This disposition of the parts is shown in plan in Fig. 3 and edge view in Fig. 4, while the position of the parts as the member B is about to be passed through the loop of the member A is indicated in Fig. 5. If it be 30 assumed that Fig. 5 shows the member B with the concave face of the loop 1 thereof toward the observer, then after the member B has been introduced through the loop 1 of member A, the member B is turned toward 35 the right or clockwise before the two loops are brought into flat engagement. If it be assumed that the member B in Fig. 5 presents the convex face toward the observer, then the turning movement of the member 40 B about its longitudinal axis is counter-clockwise as the two loops are brought into face engagement. It is thus possible to connect the two members by introducing the member B through the member A in either 45 of two positions. If, now, the member A be introduced through the member B, then the turning movements of the member A about its longitudinal axis are just the contrary to those just described with reference to the member B, and, moreover, the member A 50 must be introduced into the member B through the convex face thereof, and consequently in the opposite direction to the arrangement shown in Fig. 5 where the member B is assumed to be moving upwardly 55 through the member A. When the member B is introduced through the member A, then if the movements be represented in the same manner as in Fig. 5 the member A will be horizontal and the member A will be above 60 the member B and moving downwardly.

While when the garment to be secured together is upon the person of the wearer the movements of the two members A and B are more or less horizontal, the action is

the same as that described with reference to the showing of Fig. 5.

It thus appears that the two identical fastening devices may be interlocked in four different ways, and when once interlocked 70 cannot by any possibility become disconnected unless turned through an arc of approximately ninety degrees on two axes perpendicular one to the other.

Because of the conformation of the loops 75 1 they lie markedly flat when in interlocked relation, and there is no tendency of the introduced loop to spread the other loop as pressure is exerted only at the nose and shank or heel end of the two loops. The 80 loops 1 are so formed that each member A and B is identical with the other and both may be made by one machine, so that there is no necessity of choice when the devices are being attached to a garment as would be the case with the usual hooks and eyes which require two different machines to manufacture them and the selection of two different forms or structures when being applied to a garment. It is to be observed 85 that the internal width of each loop is less than the external shorter diameter of the other loop, while the longitudinal internal diameter of the loop is sufficient to permit the passage of one loop through the other when the shorter diameter of the one loop 90 agrees with the longer diameter of the other loop, but when the two members are on a garment and interlocked then any amount of movement of the two loops longitudinally or laterally of each other will not 95 serve to disengage one from the other, for it is only by a movement of one loop about two axes perpendicular to each other and then a further longitudinal movement of 100 the loop that it may be disengaged from the other loop when the two loops are in interlocking relation.

It is not always necessary in order to fasten two portions of a garment together 110 that two members A and B be used, for one of the members may be fastened to one flap of a garment and a button secured to the other flap. This arrangement is shown in 115 Figs. 6 and 7 where two flaps 8 and 9 of a garment are indicated, the flap 8 having secured thereto one of the members shown in the other figures, say, the member A, and this member is made fast to the flap by means of stitching 10 extending through the 120 rings 7 and other stitching 11 engaging the nose portion 2 on opposite sides of the center thereof, while a button 12 is shown as secured to the flap 9. Because of the dished shape of the loop 1 this loop will in the 125 arrangement shown in Figs. 6 and 7 offstand in the main from the flap 8 so that the button 12 may be introduced through the loop between the same and the flap 8 and the effect upon the button is similar to that of a 130

buttonhole except that the margins of the loop 1 are substantially rigid.

The structures shown in Figs. 1 to 5 are drawn to an exaggerated scale, for in most 5 instances the members A and B are in their practical form of materially less size than the illustrations, while the structure of Figs. 6 and 7 is made of a size to accommodate the button 12 and hence will usually be considerably larger than the structures shown 10 in the other figures.

What is claimed is:—

1. A garment fastener comprising two identical members each composed of a piece 15 of wire bent intermediately upon itself into a loop rounded at the free or nose end and from thence expanding to a point more than half the length of the loop from said free or nose end, then contracting until the sides 20 of the loop meet and then continuing substantially in contact to form a shank with the ends of the latter reversely bent into oppositely directed rings, the loop being bent or dished longitudinally with the part 25 between the shank and the widest portion of the loop extending to one side of the plane of the shank and that portion from the widest part to the nose end extending to the other side of said plane, and the 30 greatest breadth of the loop being less than

its internal length, whereby the nose part of one member engages over and about the shank of the other member with the nose part of said other member lying on the shank of the first member.

35

2. A garment fastener element comprising a piece of wire bent intermediately upon itself into a loop with the bend in the form of a rounded nose from which the sides of the loop gradually curve and 40 expand to a point more than half the length of the loop from the nose and from thence gradually approach, the wires being brought into side contact at the shorter end of the loop to form a shank and the terminal portions of the wire being reversely bent into oppositely directed rings, said loop 45 being bent or dished longitudinally to bring the side portions approaching the shank slightly on one side of the plane of the 50 shank and to bring the nose end to the other side of such plane.

In testimony, that I claim the foregoing as my own, I have hereto affixed my signature in the presence of two witnesses.
